SPINNING PUNCH

Richard A. Sahlin, Fairfield, Conn., assignor to Remington Arms Company, Inc., Bridgeport, Conn., a corporation of Delaware

Filed Mar. 13, 1958, Ser. No. 721,267

9 Claims. (Cl. 86—32)

This invention relates to the priming of rimfire cartridges, and contemplates a spinning punch or centrifugal dispensing impeller tool for distributing a measured charge of priming composition into a cavity in the rim of a cartridge case or shell.

The well-known rimfire cartridge is provided with a one-piece case, the head portion of which comprises a hollow outward flare defining a cavity adapted to contain the priming charge.

As more fully described in the patent to Reynolds, No. 2,313,265, the priming material is a pulverulent admixture of proper ingredients, and a measured charge thereof containing just enough moisture to form a coherent pellet is placed loose in the shell and thereafter distributed into the rim by an appropriately shaped spinning punch. It is desirable that insofar as practicable all of the mixture be placed within the hollow rim, instead of being spread over the mid-portion of the shell head or smeared on the cylindrical wall of the shell. The presence of a layer of mixture on the mid-portion of the flat head is harmless but useless since the firing pin of the gun impacts the rim. A smear of the mixture on the interior cylindrical wall of the shell is definitely unwanted. It is further desirable that the mixture be tightly compacted in the rim, to avoid dislodgment in the handling of the shells incident to the loading of completed cartridges or under impact of the firing pin.

The present invention contemplates a spinning punch or centrifugal dispensing impeller tool which is substantially more effective in the accomplishment of these objectives than punches hitherto used.

In the drawings:

Fig. 1 is an end view of a spinning punch embodying the present invention.

Fig. 2 is a fragmentary side elevation of the punch, partly within a shell having a pellet of priming mixture therein. The elevation is in the direction indicated by line 2—2 of Fig. 1.

Fig. 3 is a side elevation of the punch in the direction indicated by 3—3 of Fig. 1, the punch being in working position within the shell and having completed the distribution of the priming mixture into the shell rim.

The head portion of the shell S comprises a hollow rim or peripheral cavity C adapted to receive the priming composition which is introduced into the shell in the form of a pellet P.

The spinning punch comprises a cylindrical shank 10 of such diameter as to be received within the shell with a minimum of clearance between the cylindrical parts of shell and punch.

The tip portion of the punch, which effects the distribution of the material of pellet P into the cavity C, comprises a flat end 11 of a configuration determined by a plurality of generally circumferential cut-outs in said tip. Each cut-out comprises an end wall 12 disposed in a plane parallel to the axis of the punch, and an outwardly inclined spiral floor 13. In the drawings, two such

2

cut-outs have been illustrated, each has a maximum depth adjacent the end wall 12 and diminishes both in depth lengthwise of the punch and in width radially of the punch as it recedes from said end wall. The narrow end 5 of each floor 13 intersects the wall 12 of the adjacent cut-out in a terminal line identified by numeral 14. Each floor 13 is inclined to the end face 11 at a predetermined angle which preferably increases from the deep end to the shallow end of the cut-out. The inclination 10 of the floor is critical, and the dimensions of the slot or notch formed by the intersection 14 of each cut-out with the adjacent cut-out are critical.

Referring particularly to Fig. 3, it will be noted that margin 14 together with the bounding walls, of the cavity 15 C determine the cross-sectional area and hence the volume of the annular space which receives the priming mixture. It is important that the volume thus determined be equal to but not materially exceed the volume of the pellet P. If the mixture-receiving space is greater than 20 the volume of pellet P the mixture is only loosely distributed into the receiving space, instead of being compacted therein in the manner necessary to insure that it will remain in place in subsequent handling of the shell. On the other hand, if the receiving space is 25 materially less than the volume of pellet P, the mixture tends to be extruded into the gap between the shank of the punch and the periphery of the shell, leaving an undesirable smear on the shell interior. It is also important that the junction of the margin 14 with the periphery of the shank be substantially opposite the end of the cylindrical portion of the shell; or, in other words, that the height H of the slot defined by the margin 14 30 be substantially equal to the maximum height of the cavity C. In use, the punch rotates in the direction indicated by the arrow in Fig. 3. As the punch approaches the shell head the material of pellet P is displaced into the cut-outs and is centrifugally moved toward the small ends of the cut-outs, through cut-out 35 terminal slots defined by margin 14, and into the cavity 40 C. The angle of inclination of the cut-out floors 13 should be such as to facilitate the outward or radial movement of the mixture, rather than merely confining it between the punch and the interior of the shell head; since, as above stated, any priming composition remaining 45 on the mid-portion of the shell head is wasted. It has been found that the minimum angle of inclination of the floors 13 necessary to leave a substantially clean shell head is about 20°. At a minimum angle of 15° the cavity C can be properly filled, a layer of mixture of tolerable 50 thickness remaining on the mid-portion of the shell head. This is the inclination of each floor 13 adjacent the end wall 12. Preferably, the inclination progressively increases toward the exit margin 14, the total increase being from about 4° to about 10°. The inclination 55 of floor 13 adjacent the end wall 12 may vary from 15° to about 40°, and its inclination adjacent the margin 14 may vary from 20° to about 45°. Optimum results have been secured with a minimum floor inclination of 60 36° and a maximum of 40°; it being remembered, as above stated, that the height of the gap defined by margin 14 should not differ substantially from the maximum height of the shell rim cavity, and that the volume defined by margin 14 and the wall of cavity C should not differ materially from the volume of the charge to be 65 placed in the cavity C.

Punches made in accordance with the present invention have been found especially useful in the distribution of priming compositions which are characterized by the absence of an abrasive of the type of ground glass, these mixtures not being amenable to distribution by the kind 70 of punches hitherto used.

What is claimed is:

1. A spinning centrifugal dispensing impeller tool for distributing a measured charge of a moist and pulverulent initiating explosive composition into an annular cavity of a cartridge case having a continuous open mouth of predetermined width facing said tool; said tool comprising a cylindrical shank and a tip comprising an end face in a plane substantially perpendicular to the axis of said shank and a plurality of cut-outs intersecting said end face and the periphery of said shank, each cut-out comprising an end wall in a plane substantially parallel to said axis, and a spiral floor disposed at an angle of not less than 15° to said end face, the said tool adapted to rotate in use in a direction such that the end wall is the leading portion of the turning cut-out and the spiral floor is the trailing portion of the turning cut-out.

2. A tool according to claim 1, in which the spiral floor of each cut-out intersects the end wall of an adjacent cut-out in a line disposed at an angle not less than 20° to the plane of said end face.

3. A tool according to claim 2, in which said line intersects the periphery of said shank at a distance from said end face which is substantially equal to the height of a cavity in which the composition is being distributed.

4. A tool according to claim 2, in which the angle of said spiral floor to the plane of said end face varies uniformly from end to end of said floor.

5. A tool according to claim 4, in which the angle of the spiral floor of each cut-out to the end face of the

tool is a minimum at the end wall of such cut-out and a maximum at the intersection of said floor with the end wall of the adjoining cut-out.

5 6. A tool according to claim 5, in which the cross-sectional area of each cut-out diminishes from a maximum at the end wall of said cut-out to a minimum at the intersection of said floor with the end wall of the adjacent cut-out.

10 7. A tool according to claim 6, in which the minimum angle of said floor to the plane of the end face of said tool is between 15° and 40°, and the maximum angle of said floor to the plane of the end face of said tool is between 20° and 45°.

15 8. A tool according to claim 7, in which the volume defined by the wall of an annular cavity to be filled by said tool and the path of movement of the small end of said cut-outs is substantially equal to the volume of said measured charge.

9. A tool according to claim 8, in which the maximum dimension of the small end of each cut-out parallel to the axis of the tool does not differ materially from the width of the mouth of an annular cavity to be filled by said tool.
